UNITED STATES PATENT OFFICE

154,263

DESIGN FOR A FLASK

Maurice Goldberg, Paris, France

Application April 2, 1947, Serial No. 138,121
In France October 3, 1946

Term of patent 7 years

(Cl. D58—9)

To all whom it may concern:

Be it known that I, Maurice Goldberg, citizen of France, residing at Paris, France, have invented a new, original, and ornamental Design for a Flask, of which the following is a specification, reference being had to the accompanying drawing, forming part thereof.

In said drawings, Fig. 1 is a perspective view of the flask embodying my design. Fig. 2 is a top plan view thereof.

I claim:

The ornamental design for a flask, as shown.
MAURICE GOLDBERG.
